DELAY MECHANISM FOR TAPE
CONTROLLED APPARATUSFrank Martindell, Chicago, Ill., assignor, by
mesne assignments, to Teletypesetter Corpora-
tion, Chicago, Ill., a corporation of Delaware

Application December 30, 1952, Serial No. 328,728

11 Claims. (Cl. 199—18)

1

This invention pertains to linecasting and composing machines and more particularly to signal controlled mechanisms employed for the automatic operation and supervision thereof.

To effect automatic control of present commercial types of linecasting and composing machines it has been observed that the speed of operation which is attainable by the signal sensing and mechanical selecting mechanism exceeds that at which the linecasting machine is capable of responding. Accordingly, devices have been perfected which serve to introduce a time lag or delay factor into the operation of the automatic control mechanism so that there may result an adjustment in certain instances where the speeds of the two devices are at variance. U. S. Patents Nos. 2,062,332, 2,090,654 and 2,104,030, and co-pending application Serial No. 184,409 filed September 12, 1950, now U. S. Patent No. 2,665,799, disclose examples of mechanisms designed to obtain a coordination between automatic control devices and the principal linecasting and composing machines.

Where in ordinary composition, various character matrices are released alternatively and in irregular succession, a given matrix release device has sufficient time to restore itself to normal condition so that it may be in readiness for a succeeding operation, though in so doing it requires a somewhat longer period to complete its function cycle than that period which is required by an operating unit to complete its initiating cycle. Where a given signal is repeated one or more times, it has been observed that the occurrence of the succeeding consecutive initiating stroke is in advance of the corresponding operating cycle of the principal machine that its associated matrix release device is incapable of arriving at its normal position in sufficient time to respond thereto.

The primary object of the invention is to provide a device of simple construction which is responsive to consecutively repeated characters for introducing automatically a time delay in the operation of the control unit to conform the inherent speed of said unit to that of its associated linecasting machine.

Another object of the invention is to provide in a control unit for linecasting and composing machines, a means for distinguishing between predetermined consecutive occurrences of code signals, certain of which require the interposition of a time delay factor, and others of which require no time delay.

A further object of the invention is to provide

2

a single control means which is dually responsive to predetermined signals for controlling functions requiring different delay factors.

To effect the foregoing and other objects and features of the invention there is contemplated a repeat character and function delay mechanism for controlling the operation of linecasting and composing machines, which mechanism embodies record reading facilities including a set of tape reading elements, and having associated with it selectable instrumentalities which are responsive to consecutive identical codes to interpose a time delay factor comprising an idle tape reading cycle between each of said consecutive codes. The time delay means comprises a delay latch assembly including a selectively interposable latch which functions in response to predetermined signaling conditions to permit or prevent operation of a delay control means, and means controlled by the tape reader for rendering said latch effective to initiate a time delay operation.

For a better understanding of the present invention, reference may be had to the following description taken in conjunction with the accompanying drawings, wherein:

Fig. 1 is a longitudinal sectional view of a record reader mechanism having embodied therein principles representative of the present invention;

Fig. 2 is a plan view of the mechanism shown in Fig. 1;

Fig. 3 is an end elevation of the mechanism shown in Fig. 2;

Fig. 4 is a longitudinal sectional view of the mechanism taken on line 4—4 of Fig. 2, and

Fig. 5 is a sectional view taken on line 5—5 of Fig. 2.

The present invention, in its preferred embodiment, has been adapted to an automatic control mechanism exemplified by U. S. Patent No. 2,091,286. A record reader mechanism is indicated by the reference character 11, which consists in brief of a set of feeler levers or tape sensors 12, each provided with a feeler pin 13 and pivoted on a common shaft 14. The perforated tape or control form 30 is previously prepared in a perforating machine where it receives permutatively variant transverse rows of holes. Where the tape is employed in the control of linecasting and composing machines, each row relates to a line composition character, or to a functional operation of the composing machine as distinguished from matrix release or selection. Each row may be said to comprise the area, transversely, in which a basic number of perforations

may occur permutably. Because the presence or absence of a perforation is controlled by perforating mechanism which may be electrically supervised, these indications will be referred to according to telegraph terminology as marking or spacing signal elements respectively. For convenience in describing the sensing and transfer mechanisms of the record reader mechanism in its alternative positions corresponding terminology will be employed hereinafter.

Individual springs 15 (Fig. 1) tend normally to urge the feeler levers 12 to their extreme counterclockwise position and in this they are cyclically opposed by the action of a reciprocating bail 16 which is comprised of a transversely extending rod 17 traversing beneath the horizontal extensions 18 integrally formed with the feeler levers 12. The reciprocating bail 16 pivotally supported at an intermediate point thereof and includes a depending portion which carries a follower roller 19 spring urged against the periphery of a feeler lever operating cam (not shown) carried upon a shaft 22 driven through a clutch from a suitable source of power. Also, carried on shaft 22, but not shown, are a tape feed cam and a cam which serves to reciprocate through a transfer bail 103 periodically a set of transfer T-levers 37 as described hereinafter.

During its cycle of rotation, the tape feed cam (not shown) imparts reciprocatory movement to a follower roller carried by a tape feed lever 26. At the opposite extremity of lever 26 is pivotally carried in upright position a tape feed pawl 29. The reciprocatory movement of pawl 29 which engages the teeth of a ratchet wheel 31 imparts step-by-step motion to a feed shaft 32 which carries a sprocket feed wheel 33 whose pins coincide with the central longitudinal row of perforations conventionally provided in control forms or tapes 38 of the class employed in connection with permutation signal operating mechanism. A spring 34 urges lever arm 26 in a clockwise direction about its pivot. The movement of the tape feed pawl 29 upwardly does not cause the movement of the tape, but this is done by spring 34.

When the several feeler levers 12 are cyclically withdrawn by bail 16, the tape 38 is advanced a distance of one step by the pawl 29, following which bail 16 is returned, permitting the individual springs 15 to urge their associated levers 12 in a counterclockwise direction. The presence or absence of a hole in the tape determines finally the distance of angular movement of any of the levers 12, depending upon whether the feeler pins 13 pass through the tape or whether they are blocked by the tape as where a nonperforated position is found. The setting of the combined set of levers 12 is thereafter communicated by an associated set of transfer T-levers 37 to a set of intermediate connector bars 38. Counterclockwise movement of transfer bail or device 103 thrusts the transfer levers 37 upwardly, causing their projections or abutments 43 to encounter ones or the others of the feeler lever shoulders or abutments 44. In accordance with the positions of the several levers 12, the transfer levers 37 are rocked clockwise or counterclockwise, causing their disc extensions 45 to move the connector bars or settable members 38 correspondingly.

The connector bars or settable members 38 thereby receive a setting which corresponds to the perforations in the tape during each given cycle of operation and they in turn communicate this setting to a set of notched code selector bars 46.

Intermediate the tape sensing levers 12 there

is pivotally supported on shaft 14 a transfer setting lever 47 resembling somewhat the general class of levers 12, but different therefrom in that it is not provided with a sidewardly extending arm 5 which carries a feeler pin 13, nor is the lever 47 provided with a horizontally extending projection 18 cooperable with the bail 16, but in lieu of a projection 18, this lever 47 carries a leftwardly extending arm 48. As may be understood from the absence of a feeler pin 13, lever 47 is not positioned under the control of the presence or absence of a perforation in the tape or control form 38, but instead is positioned, as will hereinafter appear, by a selectively initiated device which is responsive to repeated character signals.

Cooperating with the transfer setting lever 47 is a transfer lever 49 similar to transfer levers 37, and a connector or settable member 51 resembling connector bars or settable members 38. Instead of bar 51 being articulated to a code selector bar 46, it is connected instead to a blocking bar 52, similar to blocking bar 52 shown in Fig. 1 of the aforementioned U. S. Patent No. 2,104,030. The projections or wards 53 of blocking bar 52 are distributed so as to clear each of the individually selectable pull bars 54 under normal conditions when any one of them is otherwise receivable with the code notches appearing in the general class of code bars 45, to block the selective movement thereof during an idle cycle of rotation, as will be more fully explained hereinafter.

In contradistinction to the general class of pull bars 54 there may be noted in Fig. 1 a pair of certain function performing pull bars 540, the purpose of which is explained in the aforementioned Patent No. 2,090,654. The lug or ward attributes of blocking bar 52 are designed to normally prevent or block the selective clearance of pull bars 540 while the projections 53 clear the general class of pull bars 54. Subsequently, when blocking bar 52 is shifted, either in accordance with the repeat mechanism or in accordance with a rail shift delay operation, a reversal of conditions is effected with the projections 53 blocking the general class of pull bars 54 but affording a selective clearance (in the event of a rail shift signal) to the rail shift pull bars 540.

The connectors 38 and 51 are slidably supported in guide blocks 55 and 65 which in turn are mounted on a back plate 56. Connectors 38 and 51 are held down by retainer plates 57 and 58. To the rear of connectors 38 and 51 (Fig. 2) and parallelly disposed thereto is a latch member 59. Disposed near each end of latch member 59 and on opposite edges thereof are open ended notches 61 and 62 which cooperate with pivot studs 63 and 64, respectively, mounted on the back plate 56. As viewed in Fig. 5, the latch member 59 is connected by a spring 66 to a detent bail member 67 which is carried pivotally on pivot studs 66 journaled in the guide block 55. Carried at the free end of the bail 67 is an adjusting screw 69 which controls the spatial relationship between the member 67 and the latch 59. A spring 70 normally imparts clockwise rotation to member 67.

Carried in the bail member 67 and adapted to span the bars 38 and 51 is a rod 71 on which are rotatably mounted a plurality of spaced rollers 72, one superposed above each of said bars 38 and 51. As more clearly shown in Fig. 4, each of the connector bars 38 and 51 carries integrally on its upper edge a saw tooth cam projection or detent 73. The positions which may be assumed by the several cam projections 73 may vary, de-

pending upon the relative position of the connector bars 38 and 51. Presented intermediate the two aforesaid positions and in the path of travel of the projections 73 are the aforesaid plurality of anti-friction rollers 72.

Referring to Fig. 2, there is positioned at substantially the center of the unit a bracket 74, which, as indicated in Fig. 3, supports a plurality of roller rod assemblies. In the embodiment of the invention shown, four such roller rod assemblies 75, 76, 77 and 78 are indicated (Fig. 1). These roller rod assemblies are arranged in pairs and each pair is disposed one above and one below the connector bars 38 and 51. The rod assemblies are biased toward each other in pairs by springs 79 (Fig. 3) so as to cause said rod assemblies to pivot about their bearings 80 in bracket 74. Each of the roller rod assemblies 75, 76, 77 and 78 carries a series of anti-friction rollers (one for each bar 51 and 52). The rearmost rollers on the rod assemblies 75, 76, 77 and 78 are in registry vertically with the latch member 59.

Pivottally carried on pivot studs 81 mounted in the guide block 65 is a bail assembly 82. Carried in the bail assembly 82 and adapted to span the bars 38 and 51 is a rod 83 on which is rotatably carried an anti-friction roller 84 which normally bears upon the upper edge of bar 51 (Fig. 4). Bail assembly 82 is normally urged counterclockwise by a spring 85. As viewed in Fig. 1, the bail assembly 82 is provided with an upwardly and rightwardly directed arm 86, the free end of which is adapted to cooperate, as will hereinafter appear, with an arm 87 extending downwardly and rightwardly from the tape feed lever 26.

The bail assembly 82 normally assumes its clockwise position, as viewed in Fig. 4, with the connector bar 51 in its rightward position and the notch 88 therein out of registry with the roller 84. Under this condition of operation the end of arm 86 is held free of the arm 87 thus permitting the tape feed lever 26 to operate in its normal manner. However, when the bar 51 is shifted to its leftward position, the notch 88 is brought beneath and in registry with the roller 84, thereby permitting bail assembly 82 to be actuated counterclockwise by its spring 85 to allow the free end of its arm 86 to bear against the end of the arm 87 of the tape feed lever 26. Then when the tape feed lever 26 moves upwardly to engage the next tooth of the ratchet 31 to feed the tape 30, the end of arm 86 will be swung beneath the arm 87 to prevent the downward, or feeding movement, of the lever 26, thus preventing tape feed at this time, for a purpose herein-after described. The bars 38 are cut away adjacent the notch 88 sufficiently to permit this operation of bail 82.

Also carried on shaft 22 is a delay operating cam 89. Cooperating with the cam 89 is a delay or plural-armed lever 90 mounted pivotally on a shaft 92 appropriately positioned in the frame of the apparatus. Lever 90 comprises a cam follower arm 93 and two depending arms 95 and 96. Lever 90 is normally urged in a clockwise direction by a spring 97. Arm 95 cooperates with latch member 59 (Fig. 5), and arm 96 cooperates with the connector bar 51 (Fig. 4). Also mounted pivotally on shaft 92 is a two-armed lever 91 comprising arms 94 and 98. Arm 94 of lever 91 cooperates with an arm 48 of selector lever 47, and arm 98 terminates in a laterally directed projection 100 which cooperates with a blocking

latch 99 mounted pivotally on a stud 101 secured to the blocking plate 56. Latch 99 is normally biased clockwise by a spring 102 attached thereto. Projection 100 also cooperates with the lower end of lever arm 96. Thus, lever 91 is normally biased counterclockwise by a spring 113.

In the operation of the apparatus according to the present invention it is assumed that the tape 30 contains a perforated message including occurrences of consecutively repeated character code signals. During the cyclic rotation of the cams on shaft 22, the tape feed cam (not shown) functions to rock the tape feed lever 26 to cause pawl 29 to actuate the tape stepping assembly to feed or step the tape the distance between two transverse rows of perforations. Between each stepping movement the tape is sensed or read by the sensing pins 13. In the rest position shown in Fig. 1 the tape sensing control cam (not shown) holds the bail 16 in its counterclockwise position whereas the rod 17 holds the tape feeler levers 12 in their retracted or clockwise position against the pull of their individual springs 15. The special lever 47, which has no arm 18 to cooperate with the rod 17, is normally held in its counterclockwise position by lever 91.

During normal operation, when there are no repeat characters, the levers 12 assume their clockwise or counterclockwise position according to the presence or absence of code holes in the tape 30, and then when the transfer bail 103 is rocked in timed relation to the tape sensing or reading operation, one or the other of the abutments 43 cooperates with one or the other of the abutments 44 to rock the T-levers 37 accordingly, to thereby shift the connector bars 38 rightwardly or leftwardly depending upon whether the T-lever 37 associated therewith was rocked counterclockwise or clockwise.

It will be recalled that as the connector bars or links 38 were shifted rightwardly or leftwardly, the cam projections 73 thereon acted, through bail 67 to rotate latch member 59 in a counterclockwise direction to bring the right end thereof (as viewed in Figs. 1 and 5) momentarily into blocking relation with the arm 95 of lever 99, thereby preventing lever 90 from following the cam 89 into the lower portion thereof. Thus, the arrestment of lever 90 caused special selector lever 47 to remain or be held in the position shown in Fig. 1 so that the abutment 105 thereon could operate with abutment 106 of its associated special T-lever 49 to cause, during the transfer operation, the lever 49 to be rotated counterclockwise to thereby shift or return the special bar 51 to its rightward position if it is not already in this position. However, as lever 90 has not yet been operated, bar 51 has not been actuated leftwardly, and accordingly, T-lever 49 is already in its counterclockwise position. Moreover, since bar 51 has not been actuated leftwardly (from its normal right-hand or rightward position, Fig. 1), the bail 82 likewise has not been actuated to cause its arm 86 to block the tape feed operation, as previously described. During the period of operation when no repeated characters or code signal groups occur, the blocking bar 52 associated with the special bar 51 assumes its rightward position wherein the code notches therein are presented below the selectable pull bars 54 to thereby permit their selective operation.

When consecutively repeated code signals are sensed in the tape 30, the blocking bar 52 becomes effective upon the initial appearance of

the repeated character in the following manner to block or prevent the selective operation of pull bars 54. During the cycle of operation of cam shaft 22, the transfer operation under the control of transfer bail 103 occurs following the tape reading operation. The delay lever 90 tends to operate during that portion of the transfer operation when the cam portions 73 are beneath the roller 72 acting to hold the bail 67 in its raised position for a purpose to be presently described.

Thus, when a code signal is to be repeated, the selectors 12 are first set in accordance with the initial appearance of said repeated code signal as just described in connection with a normal operation, since in so far as the tape reader is involved, it is not yet known that a signal is to be repeated. Accordingly, at the beginning of the repeat cycle (which is the second occurrence of the character code signal being repeated) the selector or feeler levers 12 are already set according to the code perforations of the repeated character. Therefore, during the tape sensing or reading operation under the control of bail 16, the positions of the feeler levers 12 are not changed. Then, when the transfer bail 103 is operated, the positions of the T-levers 37 and 49 are likewise not changed. Because of this, no movement of bars 38 and 51, and hence cam projections 73, has occurred and as a result thereof the latch member 59 remains in its lowered position with the right end thereof out of the path of the depending arm 96.

Therefore, the delay lever 90 is now permitted to follow the cam 89, so that when the follower roller 104 rides onto the low part of the cam, the lever 90 responds to the pull of spring 97 and is rotated counterclockwise. The timing of the movements of levers 90 and 91, and bail 103 is such that the arm 94 permits lever 47 to respond to its spring 15, and moves abutment 105 out of the path of the approaching abutment 106 to prevent interference therebetween, while the arm 96 of lever 90 is effective upon shoulder 111 of special bar 51 to shift said bar 51 leftwardly (Fig. 4).

Bar 51 in moving leftwardly actuates the special T-lever 49 to its clockwise position where it remains in readiness to effect, during the next ensuing cycle, the return of bar 51 to its rightward position. During the early part of the cycle just described, the feed pawl 29 has been elevated by the tape feed cam to its upper position preparatory to effect the stepping of the tape 39 which, as previously described, is effected upon the downward movement of pawl 29 under the control of spring 34. However, bar 51 in moving leftwardly brings its notch 88 beneath the roller and rod assembly 83—84, thereby permitting said assembly to drop into said notch, thus allowing bail 82 to rotate counterclockwise to present the end of lever arm 88 into the path of arm 87 of tape feed lever 26, thereby preventing the completion of the tape feed operation during this cycle. Bar 51 has also in its leftward shifting movement caused, through articulation 107, the leftward movement of blocking bar 52 to prevent the selective operation of pull bars 54.

The control unit or apparatus according to the present invention has now been conditioned to introduce automatically a time delay factor in the operation of the control unit with respect to the controlled machine; for example, a line-casting and composing machine. When the cam shaft 22 begins its rotation for the next ensuing

cycle the tape feeler levers 12 are permitted to sense or read the tape 30. However, since the tape 30 was not stepped during the last preceding cycle of operation, the pins 13 are cooperating with the same code areas in the tape as in the previous cycle. Accordingly, when the transfer bail 103 operates, no change in the setting of bars 38 will result, and thus no movement of cam projections 73 will occur. Bail 67, in so far as cam projections 73 on bars 38 are involved, will remain quiescent. However, with bar 51 still in its leftward position, the T-lever 49 is still in its clockwise position with its abutment 106 ready to cooperate with an abutment 105 of the special selector lever 41. Then in the above-mentioned operation of bail 103, which occurs while roller 104 is riding on the high part of cam 89, it will cause abutment 106 to strike abutment 105 to impart counterclockwise movement to T-lever 49, which in turn will cause the special bar 51 to move rightwardly. As the bar 51 is thus moved rightwardly, the cam projections 73 thereon will, in moving to the right side of the vertical center line of roller 72, cause bail 67 to rise. Latch member 59 is thereby raised to bring the right end thereof into blocking relation with arm 96 of lever 90, thus preventing the lever 90 from responding to the low part of cam 89, as previously described, and permitting special selector lever 41 to remain in the counterclockwise position shown in Fig. 1. The roller 84 is cammed out of notch 88 (Fig. 4) and arm 86 of bail 82 acts to unblock the tape feed lever 26. Thus, during this time delay cycle, the bar 51 was restored to its rightward position, and the tape feed lever 26 was unblocked to permit the tape 30 to again be stepped under the pull of spring 34 to present the next row of perforations to the pins 13.

From the foregoing it is observed that the bar 51, like bars 38, has no normal rightward or leftward position. Bars 38 are shiftable rightwardly and leftwardly solely by the transfer device 103; but bar 51 is dually controlled, that is, leftwardly by the delay lever 90 and rightwardly by the transfer mechanism 103.

If the next row of perforations is similar to the previous row, that is, if the code signal is again repeated, then during the transfer cycle 50 the bars 38 are not effected but remain in their set positions because the positions of the feeler levers 12 has not been changed. As a result, the latch lever 59 is not raised to bring its right end into blocking relation with the arm 96 of delay lever 90, and as previously set forth, the bar 51 is actuated leftwardly. The block bar 52 is thus positioned to prevent the selective operation of pull bars 54. Accordingly, the next succeeding cycle is a time delay cycle wherein the code signal in the tape 30 is sensed a second time without effecting a selective operation of the pull bars 54, thus permitting the functional operation of the linecasting machine, initiated during the previous cycle, to be completed. During the instant cycle, 60 however, the special bar 51 is returned to its rightward position and the tape feed lever 26 is unblocked, and the tape 30 is stepped as described hereinbefore. Thus, so long as a repetition of signals persists, the tape 30 will be stepped every other cycle, with a time delay (or non-stepping) cycle interposed automatically between each said stepping cycle.

In accordance with the present invention, 70 facilities are also provided to prevent or block

the operation of the plural armed lever 90 in response to certain repeated character signals; for example, the so-called "blank" and "rub-out" signals which do not initiate cycles of operation of the linecasting machine which require a time delay factor to be interposed. That is, when repeated "rub-outs" or "blanks" occur in the tape it is not desirable to delay the feeding of the tape 30, since no matrices will be dropped in the linecasting machine. To achieve this result, two 10 roller rod assemblies are provided; namely, assembly 77 responds to the "rub-out" code signal, and assembly 78 responds to the "blank" code signal. Thus, in response to a setting of the bars 38 and 51 in accordance with the "rub-out" code signal all the bars 38 will assume their left-hand or marking position, and the bar 51 will remain in its rightward or spacing position. Assembly 15 77 will then respond to the pull of its spring 79 and rise into the alignment of code notches, and in so doing the rear roller on the rod assembly 77 acts to raise the latch member 59 to present the right end thereof into the path of the arm 96 of delay lever 90, thereby preventing the leftward movement of bar 51, and the blocking bar 52 therefore remains in its non-blocking or rightward position. Accordingly, when the bar 51 thus remains in its rightward position, the bail 82 (Fig. 4) is held in its clockwise position with the arm 86 thereof out of blocking relation with the tape feed lever, whereupon regular tape feed 20 continues.

In a similar manner, when the bars 38 are set in accordance with a "blank" code signal, the assembly 78 is selected (instead of the assembly 77) to effect the same result upon latch member 59 and delay lever 90 as was effected upon the selection of assembly 77 (just described). When repetition of other characters occurs the selection of both the "rub-out" and the "blank" roller rod assemblies 77 and 78, respectively, is suppressed, and the delay action is carried out as previously described.

The present invention also provides facilities for selecting a thin space (or fixed space) matrix and a spaceband sequentially in response to an "add-thin-space" code signal. Reference may be had to U. S. Patent No. 2,287,793 for a more detailed account of the application of an add-thin-space device analogous to the present embodiment of the invention to a linecasting and composing machine. In response to the setting of bars 38 and 51 corresponding to the "add-thin-space" code signal, an alignment of notches will occur beneath the roller rod assembly 76 permitting assembly 76 to fall thereinto under the influence of its spring 79. The latch member 59 is thus urged downwardly under pressure of said spring 79 to bring the right end of said member out of the path of the depending arm 96 of delay lever 90. Lever 90 is thus free during the cycle of operation to rotate clockwise, and through arm 96, to shift the special bar 51 leftwardly, as previously described. In the add-thin-space arrangement according to the present invention, the bar 51 is connected through connection 107 to a blocking bar, similar to bar 118 shown in Fig. 3 of said Patent No. 2,287,793, which is provided with a pair of lugs (similar to lugs 119 and 121 of said patent) which control alternatively the selection of the pull bars 54 assigned to the spaceband and thin (or fixed space) space selections. The blocking bar (comparable to said bar 118) thus in moving to the left permits selection of thin (or fixed) space and prevents the selection 70

of a spaceband. At the same time, the delay lever 90 is permitted to rotate clockwise by cam 89 so that its arm 94 allows the delay selector lever 47 to rotate in a counterclockwise direction 5 to clear the T-lever 49 which therefore allows the bar 51 to be moved to the left, as previously described. Notch 88 of bar 51 is brought beneath roller 84 of bail 82 to permit bail 82 to rotate counter-clockwise to cause its arm 86 to block the tape feeding operation. Also, at the same time, when the bar 51 moves to the left, under the influence of power storage means or springs 97, the assembly 76 is cammed out of the notch 108, so that the latch member 59 is no longer held down by the roller rod assembly 76. Then, when the bar 51 is returned in the next cycle to its rightward position, as previously described, by the transfer mechanism 103, the tape feed mechanism is unblocked, and the blocking bar 20 (similar to said bar 118) is shifted to prevent the selection of a thin (or fixed) space matrix and to permit the selection of a spaceband on the second cycle.

The present invention further provides facilities for introducing a time delay factor in the operation of the control unit with respect to the duplex rail shift mechanism in a line casting machine. Reference may be had to U. S. Patent No. 2,090,654 for a detailed description of the duplex 25 rail delay mechanism to which the present invention is applicable. In response to the setting of bars 38 and 51 corresponding to either the "upper rail" or "lower rail" code signal, an alignment of notches will occur beneath the roller rod assembly 75 permitting assembly 75 to fall thereinto under the influence of its spring 79. This downward movement of assembly 75 will act to depress latch member 59 and hold it down (since spring 102 is stronger than spring 66), thereby allowing 30 the delay lever 90 to rotate in a clockwise direction, due to the fact that the arm 95 thereof is at this time unblocked. As previously described, the bar 51 is thus actuated leftwardly to shift the blocking bar 52 correspondingly to prevent selection of the upper rail and lower rail pull bars 540 35 of the series of pull bars 54. In this movement of bar 51, the projection 115 (Fig. 4) thereon is moved to the left of the vertical centerline of assembly 75, for a purpose which will presently appear.

When the blocking bar connector 51 is thus moved leftwardly, the notch 88 thereon is presented beneath the roller 84 of bail 82 to permit bail arm 86 to block or prevent the tape feeding function, as described hereinbefore. While the bar 51 is in its leftward position the assembly 75 remains down, and accordingly the spring 102 urges the latch 99 clockwise about pivot 101 into latching relation with lateral portion 100 of the two-armed lever 91, so that, when the delay lever 90 is rotated clockwise by its spring 97, its arm 96 will coact with the lateral portion 100 to rotate the lever 91 clockwise so as to cause said portion 100 to come into latching engagement with the shoulder 109 (Fig. 4) of latch 99. Therefore, so long as latch 99 is permitted to remain in its downward position under the pull of spring 102, the lever 91 will be held in its clockwise position. As a result thereof, arm 94 of lever 91 will permit special selector lever 47 to assume its counterclockwise position with abutment 105 out of register with abutment 106. Then upon ensuing cycles of operation the bar 51 will not be returned to its rightward position so long as lever 91 remains latched up by latch 99,

11

and accordingly the feeding of the tape 30 will continue to be prevented.

In the control of linecasting and composing machines, most functions are concerned with the selective release of matrices from their respective channels in the storage magazine after which they are permitted to gravitate to a lower level and be assembled in a carriage device known in the art as a matrix assembling block. Each matrix is customarily provided with two related character impressions or intaglio located one above the other in the operative position of the matrix, while the assembling block is provided with a shiftable or displaceable upper level supporting rail which, by its presentment to, or withdrawn from, the ingress portion of the assembling block, may be made to determine the position in which subsequently received matrices shall thereafter be supported within the block. The position of each matrix, one determined by the condition of the aforesaid shiftable rail, prevails throughout the composing operation and until an assembled line of matrices is thereafter transported by the elevator to the casting mechanism.

A certain time interval is required from the instant during which a matrix is released until the instant at which it is received in the assembling block of the elevator of the linecasting machine. As a result, when it is desired to effect the movement of the assembling block slide rail following the reception of a certain matrix to vary the manner of reception of the next matrix or matrices, means must be provided for suspending the movement of the rail until the preceding matrix has had time to complete its travel and be properly received in the assembling block. Otherwise, with a spontaneous movement of the rail the reception of the preceding matrix might be effected in a position other than the one intended for it.

The afore-mentioned Patent No. 2,090,654 discloses a mechanism for introducing a time delay period equivalent to or exceeding the time necessary for the travel of one matrix from its storage magazine to the assembling block before the shiftable rail is operated to receive the next matrix or matrices. This mechanism is exemplified in the present disclosure by the ratchet 110 shown in Fig. 1. Accordingly, the disclosure of said patent is deemed to be incorporated by reference into the present description. Briefly, however, a step-by-step rotation is imparted to the ratchet 110 by a pawl member 113 operatively associated with the tape feed mechanism, so that a pin 112 on ratchet 110, after a predetermined number of cycles of operation of the tape reader functions to cooperate with a means for swinging the lever 47 back to its clockwise position whereat abutment 105 is again positioned above abutment 106. Then upon the next ensuing cycle of operation of the transfer mechanism 103, the coaction of abutments 105 and 106 causes bar 51 to be shifted rightwardly, so that the projection 115 will cam the rod assembly 75 upwardly momentarily to effect the unlatching lever 91 by the latch 99. Also, the bail 82 will be cammed out of notch 88 to cause the arm 86 to be swung out of blocking relation with the arm 87 of the tape feed lever 26. When the blocking bar similar to bar 52, having the upper rail and lower rail blocking projections thereon, is thus shifted rightwardly, the upper and lower rail pull bars (of the group of pull bars 54) are unblocked so that the selec-

12

tion of the upper rail or lower rail may not be effected.

It is understood that the above described arrangements are simply illustrative of the application of the principles of the invention. Numerous other arrangements may be readily devised by those skilled in the art which will embody the principles of the invention and fall within the spirit and scope thereof.

What is claimed is:

1. In a tape controlled selector mechanism, means for sensing code indicia in a tape, transfer means, a plurality of settable members set by said transfer means according to the operation of said tape sensing means, a special element associated with said tape sensing means, a special settable member, cyclically operable cam means, cam follower means comprising a blockable portion and a setting portion, control means controlled by said tape sensing means, said control means comprising cam projections on said settable members, a rocker member controlled by said projections, and a latch member articulated to said rocker member, said latch member adapted to cooperate with said blockable portion, and spring means effective through said cam follower means following the nonoperation of said latch member by said rocker member under an inert condition of said plurality of settable members indicative of consecutive occurrences of similar code indicia in the tape, whereby said special settable member is enabled to be set in one manner solely by the setting portion of said unblocked cam follower means, and to be set in a reverse manner by the coaction of said special element and said transfer means in response to the blocked condition of said cam follower means indicative of the resumption of normal occurrences of variant code indicia in the tape.
2. In a tape controlled selector mechanism, means for sensing code indicia in a tape, transfer means, a plurality of settable members set by said transfer means according to the operation of said tape sensing means, a special element associated with said tape sensing means, a special settable member, cyclically operable cam means, cam follower means comprising a blockable portion and a setting portion, and control means controlled by said tape sensing means, said control means comprising cam projections on said settable members, a rocker member controlled by said projections, and a floating latch member yieldably articulated to said rocker member, said latch member adapted to cooperate with said blockable portion, and power storage means effective through said cam follower means following the nonoperation of said latch member by said rocker member under an inert condition of said plurality of settable members indicative of consecutive occurrences of similar code indicia in the tape, whereby said special settable member is enabled to be set in one manner solely by the setting portion of said unblocked cam follower means, and to be set in a reverse manner by the coaction of said special element and said transfer means in response to the blocked condition of said cam follower means indicative of the resumption of normal occurrences of variant code indicia in the tape.
3. In a tape controlled selector mechanism, cyclically operable means for sensing code indicia in a tape, transfer means, a plurality of settable members set by said transfer means according to the operation of said tape sensing

13

means, a special element associated with said tape sensing means, a special settable member, cyclically operable cam means comprising a blockable portion and a setting portion, cam follower means, control means controlled by said tape sensing means, said control means comprising cam projections on said settable members, a rocker member controlled thereby and a latch member articulated to said rocker member, said latch member adapted to cooperate with said blockable portion, energy storage means effective through said cam follower means following nonoperation of said latch member by said rocker member under an inert condition of said plurality of settable members indicative of consecutive occurrences of similar code indicia in the tape, whereby said special settable member is enabled to be set in one manner solely by the setting portion of said unblocked cam follower means, and to be set in a reverse manner by the coaction of said special element and said transfer means in response to the blocked condition of said cam follower means indicative of the resumption of normal occurrences of variant code indicia in the tape, and means controlled by said special settable member to preclude the operation of said tape sensing means to thereby introduce a time delay factor comprising an idle tape reading cycle.

4. In combination, tape sensing means, transfer means, a plurality of settable members set by said transfer means according to the operation of said tape sensing means, cam means, cam follower means comprising a blockable portion and a setting portion, a special settable member controlled by said setting portion, blocking means comprising a rocker member and a floating element yieldably articulated thereto, said floating element cooperable with said blockable portion under certain predetermined operating conditions to prevent control of said special settable member by said cam follower means, spring means associated with said cam follower means for rendering said setting portion effective to move said special settable member during the unblocked condition of said cam follower means, and means associated with said plurality of settable members for controlling the effectiveness of said blocking means.

5. In combination, tape sensing means, transfer means, a plurality of settable members set by said transfer means according to the operation of said tape sensing means, cam means, cam follower means comprising a blockable portion and a setting portion, a special settable member controlled by said setting portion, blocking means comprising a rocker member and a floating element yieldably articulated thereto, said floating element cooperable with said blockable portion under certain predetermined operating conditions to prevent control of said special settable member by said cam follower means, power storage means associated with said cam follower means for rendering said setting portion effective to move said special settable member during the unblocked condition of said cam follower means, means associated with said plurality of settable members for controlling the effectiveness of said blocking means, and means controlled by said special settable member to preclude the operation of said tape sensing means to thereby introduce a time delay factor comprising an idle tape reading cycle.

6. In a tape controlled selector mechanism, means for sensing code indicia in a tape, transfer

14

means, a plurality of settable members set by said transfer means according to the operation of said tape sensing means, a special element associated with said tape sensing means, a special settable member, cyclically operable cam means, cam follower means comprising a blockable portion and a setting portion, latchable means yieldably associated with said cam follower means for controlling said special element, control means controlled by said tape sensing means, said control means comprising cam projections on said settable members, a rocker member controlled by said projections, and a floating member yieldably articulated to said rocker member, said floating member adapted to cooperate with said blockable portion, power storage means effective through said cam follower means following the nonoperation of said floating member by said rocker member under an inert condition of said plurality of settable members indicative of consecutive occurrences of similar code indicia in the tape, whereby said special settable member is enabled to be set in one manner solely by the setting portion of said unblocked cam follower means, and to be set in a reverse manner by the coaction of said special element and said transfer means in response to the blocked condition of said cam follower means indicative of the resumption of normal occurrences of variant code indicia in the tape, latch means effective upon actuation of said special settable member in said one manner to latch said latchable means to render said special element ineffective upon said special settable member, means controlled by said special settable member to preclude the operation of said tape sensing means, and a timing mechanism controlled by said tape sensing means and effective upon said special element to introduce a time delay factor comprising a predetermined number of idle tape reading cycles.

7. In combination, tape sensing means, transfer means, a plurality of settable members set by said transfer means according to the operation of said tape sensing means, cam means, cam follower means comprising a blockable portion and a setting portion, a special settable member controlled by said setting portion, blocking means comprising a rocker member and a floating element yieldably articulated thereto, said floating element cooperable with said blockable portion under certain predetermined operating conditions to prevent control of said special settable member by said cam follower means, power storage means associated with said cam follower means for rendering said setting portion effective to move said special settable member during the unblocked condition of said cam follower means, and cam means on said settable members for controlling the effectiveness of said blocking means.

8. In combination, tape sensing means, transfer means, a plurality of selectively settable members set by said transfer means according to the selective control of said tape sensing means, cam means, cam follower means comprising a blockable portion and a setting portion, a special settable member controlled by said setting portion, blocking means comprising a rocker member and a floating element yieldably articulated thereto, said floating element cooperable with said blockable portion under certain predetermined selective conditions to prevent control of said special settable member by said cam follower means, spring means associated with said cam follower means for rendering said setting portion effective to move said special settable member during the

15

unblocked condition of said cam follower means, cam means on said settable members for controlling the effectiveness of said blocking means, and a plurality of elements selectable by said plurality of settable members, said elements effective under other predetermined selective conditions to further control the effectiveness of said blocking means.

9. In combination, tape sensing means, transfer means, a plurality of settable members set by said transfer means according to the operation of said sensing means, cam means, cam follower means comprising a blockable portion and a setting portion, blocking means comprising a rocker member and a floating element yieldably articulated thereto, said floating element cooperable with said blockable portion under certain predetermined operating conditions to prevent control of said special settable members by said cam follower means, spring means associated with said cam follower means for rendering said setting portion effective to move said special settable members during the unblocked condition of said cam follower means, cam means on said settable members for controlling the effectiveness of said blocking means, and means controlled by said special settable member to preclude the operation of said tape sensing means to thereby introduce a time delay factor comprising an idle tape reading cycle.

10. In a tape controlled selector mechanism, means for sensing code indicia in a tape, transfer means, a plurality of settable members set by said transfer means according to the operation of said tape sensing means, a special element associated with said tape sensing means, a special settable member, cyclically operable cam means, cam follower means, latchable means yieldably associated with said cam follower means for controlling said special element, control means controlled by said tape sensing means, said control means comprising cam projections on said settable members, a rocker member controlled by said projections, and a floating member yieldably articulated to said rocker member, power storage means effective through said cam follower means following the nonoperation of said floating member by said rocker member under an inert condition of said

16

plurality of settable members indicative of consecutive occurrences of similar code indicia in the tape, whereby said special settable member is enabled to be set in one manner solely by said unblocked cam follower means, and to be set in a reverse manner by the coaction of said special element and said transfer means in response to the blocked condition of said cam follower means indicative of the resumption of normal occurrences of variant code indicia in the tape, latch means effective upon actuation of said special settable member in said one manner to latch said latchable means to render said special element ineffective upon said special settable member, means controlled by said special settable member to preclude the operation of said tape sensing means, and a timing mechanism controlled by said tape sensing means, said timing mechanism effective upon said special element to determine the period of preclusion of operation of said tape sensing means, whereby a time delay factor is provided.

11. In combination, tape sensing means, transfer means, a plurality of settable members set by said transfer means according to the operation of said tape sensing means, cam means, cam follower means comprising a blockable portion and a setting portion, a special settable member controlled by said setting portion, blocking means comprising a rocker member and a floating element yieldably articulated thereto, said floating element cooperable with said blockable portion under certain predetermined operating conditions to prevent control of said special settable member by said cam follower means, power storage means associated with said cam follower means for rendering said setting portion effective to move said special settable member during the unblocked condition of said cam follower means, and means associated with said plurality of settable members for controlling the effectiveness of said blocking means.
